UNITED STATES PATENT OFFICE

WILLIAM C. KENNEY AND GEORGE M. KENNEY, OF CRANSTON, RHODE ISLAND, ASSIGNEES TO KENNEY MANUFACTURING COMPANY, OF CRANSTON, RHODE ISLAND, A CORPORATION OF RHODE ISLAND

TRAVERSE EQUIPMENT

Application filed February 6, 1932. Serial No. 591,350.

This invention relates to that class of certain fixtures known to the trade as "traverses" wherein a pair of curtains, portières or other hangings are suspended at their upper edges from a rod by means of a plurality of traveling idlers and a pair of master carriers sliding within the rod. The master carriers, and with them the hangings, are adapted simultaneously to be drawn together or apart by means of a pull cord operating over guide pulleys mounted in or on the rod.

In general, the object of our present invention is to improve and simplify such traverse equipment to the end that the traverse shall operate freely at all times without danger of jamming or cramping the moving parts or entangling the operating cord with said moving parts.

To accomplish this object we have developed master and idler carriers of entirely new structure and result. Our carriers are so designed as to prevent all possibility of the operating cord from becoming caught between them and their trackways and thus causing the equipment to jam. Specifically both the master and idler carriers used in our traverse are provided with eyes or loops in which the operating cord is positively confined and guided, thus eliminating the danger of the cord becoming entangled with the moving carriers.

Our master carriers, moreover, are provided with a locking device of entirely new type by means of which the operating cord can be instantly locked to and unlocked from the master carrier at any position of adjustment of the master carrier along the trackway without danger of cutting, fraying or otherwise damaging the operating cord.

In order to obtain such adjustment in traverses now on the market it is necessary either to use set screws which bite into the cord when tightened and soon fray or cut it, or else to use locking devices which are so difficult of access as to require the rod to be removed from its operating brackets in order to manipulate said locking devices.

Each master carrier of our traverse is constructed to guide and confine one length of the looped operating cord and to be locked

to and unlocked from the other length of such cord. Thus the cord is not only prevented from becoming entangled with the moving carrier but the carrier may be locked to and unlocked from the cord, whenever it is desired to adjust the carrier to a new position along the rod, without danger of fraying or cutting the cord and without requiring that the rod be dismounted from its supporting brackets.

Each idler carrier of our traverse is constructed to guide and confine both lengths of the operating cord, and additionally is provided with means adapted positively to prevent the idlers from tilting into a position wherein they will jam against the inside wall of the rod.

The construction and manner of assembling and operating our traverse, together with a form of traverse which has been found both satisfactory under actual service conditions and well adapted to the requirements of commercial manufacture, is described and illustrated in the accompanying specification and drawings, and its characteristic features of novelty particularly pointed out in the appended claims.

In the drawings:—

Fig. 1 is a fragmentary elevation of a traverse installation in accordance with our concept.

Fig. 2 is a sectionalized showing of the traverse assembly of Fig. 1.

Fig. 3 is a fragmentary perspective of a section of our novel traverse rod, removed.

Fig. 4 is a perspective view of one of the master carriers, removed from the assembly, and unlocked.

Fig. 5 is a fragmentary side view thereof, and showing the parts in their locked position.

Fig. 6 is a section on the line 6—6 of Fig. 5.

Fig. 7 is a perspective view of one of the idler carriers, removed.

Fig. 8 is a section on the line 8—8 of Fig. 2, and

Fig. 9 is a perspective view of one of the rod supporting brackets removed.

According to our present invention, we utilize the U-shaped rod of the George M.

Kenney Patent No. 1,723,975, of August 6, 1929, as the rod element of our present novel combination.

Such rod may be either a single length or 5 may consist of two or more telescopic members as indicated at A and B in Figs. 1 to 3. In either case, the rod presents a pair of spaced side walls 1 connected across their upper edges by the top wall 2, and terminating 10 at their lower edges in spaced inturned flanges 3 which afford trackways for the master and idler carriers of the traverse.

The space 4 separating said flanges is substantially central of the rod so that the weight 15 of the curtains or other hangings H and H' is disposed in substantially the vertical axis of the rod and in a plane parallel to the window or other opening to be covered.

Unlike the usual C-shaped rod heretofore 20 so generally employed, our novel U-shaped rod is reversible, both side walls 1 being patterned, so that either may be used as the front or outer wall. The traverse rigging is assembled complete in the rod at the factory 25 and a pair of brackets 5 is furnished with each fixture.

These brackets are detailed in Fig. 9 and each consists of an attaching base 6 having a rod seating formation 7 providing a U-shaped 20 recess of reversed disposition as to the U of the rod so that the ends of the rod may be entered into the same from above, the rod ends being slotted as at 8 (Fig. 3) and the U-shaped recess of each bracket being provided with a centering and locking prong 9 adapted to be penetrated through a rod slot 8. When the rod is mounted in the brackets, its rounded bottom edges 3' rest against the rounded bottom edges 7' of the recesses 7, so that the weight of the rod and its hangings is borne entirely by said bottom edges 7'. 45

The bracket per se however forms no part of our present invention except in its combinative relation to the rod.

Slidable inside the rod on the continuously 50 horizontal uninterrupted trackways provided by the free edges of the upturned flanges 3 of the rod is a pair of master carriers indicated generally at 10 and 10' and a plurality of idler carriers indicated generally at 11. These carriers have curtain attaching portions depending through the slot or opening 4' spacing the flanges 3 so that the weight of the hangings is disposed centrally of the rod.

The master carriers are duplicates of each other, as are the idlers 11, and hence a description of one of each will suffice.

Each master carrier comprises a relatively thin strip or body portion, preferably of metal. Where of metal it may be formed, preferably along its upper edge as a pair of spaced loops or eyes 12 and 13, which are preferably located, respectively, at either end of said upper edge. These eyes afford anti-friction guides for the looped operating cord,

the exposed operating ends of which are indicated at 14 and 15.

Beyond the eyes 12 and 13, each carrier extends upwardly as a pair of division webs 12' and 13' at the extreme ends of the carrier. One purpose of the webs is to space the lengths of the operating cord apart. The cord lengths pass over rollers 16 and 17 mounted on each carrier at said webs. Another purpose of the webs is to prevent the carriers from striking against the top wall of the rod.

The rollers 16 and 17 ride on the trackways provided by the free edges of the upturned flanges 3 of the rod and the lengths 80 of the operating cord rest on the upper surfaces of these rollers.

Inwardly of the eyes or loops 12 and 13 the upper edge of each master carrier is provided with a fixed pair of spaced aligned cord guides 18 and 19 between which is a movable cord guide 20.

The movable cord guide 20 is capable of limited movement in both a lateral and a vertical direction relative to the fixed guides 18 and 19. When moved laterally towards the left and downwardly from the position of Fig. 4 to that of Fig. 5, said guide 20 clamps or binds the inserted length of cord therein, thus locking the master carrier to the cord. When the guide 20 is moved to the release position of Fig. 4, the cord is unlocked so that the carrier may be adjusted along the rod to a new position and again locked.

The movement of the guide 20 from locked to unlocked position and vice versa may be conveniently accomplished by forming the guide 20 as an integral part of a manually operable locking lever 21 mounted on the body portion of the carrier for limited motion in both a lateral and a vertical direction.

Stamped or otherwise marked on the body of the carrier itself are oppositely pointing arrows and the legends, "To lock" and "To release", indicating the locked and unlocked positions of the lever when swung laterally. When swung to the locked positions the lever is also drawn slightly downwardly to move the guide 20 out of alignment with the guides 18 and 19 (Fig. 5) thereby binding the length 115 of the cord 14 in said figure. When swung to the unlocked position, the lever also moves slightly upwardly to carry the guide 20 back into substantial alignment with the guides 18 and 19 (Fig. 4) thereby releasing the cord 14 in said figure.

For this purpose, the lever is extended downwardly at one side of the carrier substantially parallel to the plane thereof, and is provided at its lower end with a stud which is disposed through a cam slot 22 formed in the body of the carrier and is provided with rounded heads or operating buttons 23 by means of which the lever may be manipulated.

The metal of the carrier above the slot 22 is cut away as indicated at 24 and is depressed laterally slightly above said cut-out 24 as indicated at 25 to provide a guiding bar to guide the lever in its back and forth swinging motion, the body of the lever above the buttons 23 and beneath the guide 20 being slightly depressed laterally to bear against said bar 25.

10 One end of each master carrier is offset, as indicated at 26, to permit it to clear the reversely offset end of the opposite master carrier when the carriers are brought together whereby the hangings may be overlapped 15 upon each other when closed. These offset ends, as well as the opposite ends of the master carriers are apertured as at 27 to receive any suitable curtain fastening device, as a hook or thread.

20 Each idler carrier 11 (Fig. 7) comprises a depending hanger 28 and two sets of rollers 29 and 30 at either end of the upper portion of said hanger, which is formed as a cord guiding eye or loop 28^a. The lower end of hanger is perforated as at 31 for the attachment of the curtain. Above said hole 31 and below the rollers 29 and 30, the hanger is provided with a third set of rollers 28'. These rollers track along the outer edges 3' of the rod and prevent the idler from tilting inside the rod and thereby jamming the operating cords between the idlers and the top wall of the rod.

25 The cord rigging is standard. At the right hand end of the rod in Fig. 2 there is mounted a double pair of alined pulleys 32, only one of which shows however in said figure. At the left hand end of the rod is mounted a single pulley 33.

30 Both lengths 14 and 15 of the pull cord are looped over pulley 33 and each length is individually passed over one or the other of the pair of pulleys 32.

35 Considering the disclosure of Fig. 2 as typical, from the far pulley 32 in that figure over which the length 14 for example passes, said length is carried through the eye 28^a of the idler carrier 11 of which there may be more than one, and thence loosely through the eyes 13 and 12 of the master carrier 10' at the far side of the webs 13' and 12' but not through the loops 19, 20 or 18 of said carrier, thence through the eye 13, fixed loop 18, locking loop 20, fixed loop 19, and eye 12 of the other master carrier 10, thence through the eye 28^a of the idler carrier 11, of which there may be more than one lying between said carrier 10 and the pulley 33, thence over pulley 33, thence as return length 15 back through the eye 28^a of said idler carrier or carriers, thence loosely through the eyes 12 and 13 of master carrier 10 at the near side of the webs 12' and 13', thence through the loops 19, 20 and 18 of the other carrier 10' at the near side of the webs 12' and 13', thence

through the eye 28^a of the idler carrier or carriers 11 which lie between said carrier 10' and the pulleys 32, and finally over the nearer of said pulleys 32.

40 By means of this arrangement, the cord lengths are positively guided and confined so as not to become entangled with the moving carriers while at the same time, the master carriers may be readily locked to and unlocked from the cord to permit the carriers 75 to be adjusted to new positions along the rod, without danger of fraying or cutting the cord and without requiring the disassembly of the rod from its supporting brackets.

45 The exposed ends of the operating cord 80 depend from the rod at one end thereof, as shown in Fig. 2, and constitute pull ends by means of which the carriers may be slid along the rod, the master carriers traveling towards each other when one end 14 of the 85 cord is drawn downwardly and away from each other when the opposite end 15 of the cord is drawn downwardly.

50 If after a rod has been installed, as in Fig. 1, for example, it is found desirable to reverse its position so that the pull cord ends will be at the left hand end of the rod instead of the right, the rod in its entirety is simply lifted out of its supporting brackets, turned around, and replaced in the brackets. 85

55 This may be done without disturbing the setting of the carriers or removing and replacing any of the operating parts of the traverse, the master carriers being stamped on both sides with the operating directions 90 as to locking and releasing so that either side which happens to be outermost presents the same operating directions.

60 Our rod is of the maximum rigidity and strength, due to its U-shape, and hence may 105 be extended to any practicable length without danger of sagging or buckling.

65 The curtains hang centrally of the rod and hence our carriers may be manipulated back and forth with far less effort, due to the 110 substantial reduction of friction. In our rod, the friction is equally distributed over both parallel flanges 3 of the rod which afford a pair of track rails disposed in the same horizontal plane. 115

70 Various modifications in the construction and operation of our device may obviously be resorted to if within the spirit and scope of our invention as defined by the appended claims. 120

75 What we therefore claim and desire to secure by Letters Patent is:—

1. In traverse equipment, a rod, a master and an idler carrier movable on said rod, said master carrier having an eye adjacent each end thereof and a movable locking formation between said eyes and independent thereof, and said idler carrier also having an eye, and a looped operating cord for said master carrier, one length of said cord passing 125

- through the eyes of said master carrier and the other length of said cord passing both through said eyes and the locking formation of said master carrier but independent of 5 said first-named length, and both lengths passing through the eye of said idler carrier.
2. Traverse equipment as claimed in claim 1 wherein the master carrier adjacent said eyes is provided with rollers, constituting 10 both guides over which the cord lengths pass to said eyes and anti-friction bearings adapted to track on said rod.
3. Traverse equipment as claimed in claim 1 wherein the idler carrier below said eye 15 is provided with rollers adapted to track on said rod.
4. In traverse equipment, a master carrier having a pair of spaced alined eyes adjacent its ends, and a looped operating cord, both 20 lengths of which are received and guided in said eyes.
5. A master carrier as claimed in claim 4, wherein the carrier has rollers in advance of said eyes and below the same over which the 25 operating cord passes to said eyes.
6. In traverse equipment, a master carrier having a pair of spaced alined eyes adjacent its ends adapted to receive and guide an 30 operating cord along said upper edge, rollers in advance of said eyes and below the same over which the operating cord passes to said eyes, and division webs above said rollers and disposed substantially centrally of said eyes and in advance of the same.
- 35 7. A master carrier as claimed in claim 6, wherein said carrier between said eyes is formed with a fixed pair of spaced alined cord guiding loops and a movable cord locking loop is disposed in the space between said fixed pair of loops and is movable into and out of registry therewith.
- 40 8. In traverse equipment, a master carrier having a fixed pair of spaced cord guides, and a movable cord lock disposed in the 45 space between said fixed guides for movement into and out of registry therewith.
- 45 9. In traverse equipment, a master carrier having a fixed pair of spaced cord guides, and a cord lock comprising a lever mounted 50 on said carrier for movement both laterally and vertically relative thereto, said lever having at its upper end a movable cord guide disposed between said pair of fixed cord guides and shiftable into and out of registry therewith by and in the movement of said 55 lever to lock or release position relative to the cord.
- 55 10. A master carrier as claimed in claim 9, wherein the body of the carrier is formed 60 with a cam slot and the lower end of said lever is provided with a finger-operating stud disposed through said slot.
- 65 11. In traverse equipment, an idler slide having a head formed with a cord guiding eye 65 through which an operating cord is adapted
- to be passed, said head terminating in a depending drapery attaching portion, an anti-friction element at either end of said head below said eye and spaced thereby from each other, and an anti-friction element carried by said depending drapery attaching portion and disposed below said anti-friction elements of the head and substantially centrally thereof.
- 70 12. In traverse equipment, a U-shaped rod having spaced solid front and rear walls, a connecting top wall, and a pair of spaced track-forming flanges extending inwardly and upwardly from its lower edge to provide a substantially continuous, unbroken trackway from end to end of the rod, a master carrier having a roller bearing on said track-forming flanges, and having a pendent drapery attaching portion disposed centrally through the space separating said flanges whereby the weight of the carrier and attached drapery is disposed in the vertical axis of the rod, said master carrier having also a cord-guiding formation and an independent cord-locking formation, and a looped operating cord having one length confined and guided by said cord-guiding formation and having its other length both clamped by said cord-locking formation of the master carrier and guided by said cord-guiding formation thereof.
- 75 13. In testimony whereof we affix our signatures.
